UNITED STATES PATENT OFFICE.

CHARLES E. WALTER, OF CLEVELAND, OHIO.

CAR ROOF.

Application filed February 7, 1921. Serial No. 442,990.

To all whom it may concern:

Be it known that I, CHARLES E. WALTER, a citizen of the United States, residing at Cleveland, in the county of Cuyahoga and State of Ohio, have invented a certain new and useful Improvement in Car Roofs, of which the following is a full, clear, and exact description, reference being had to the accompanying drawings.

10 This invention is directed to improvements in railroad car construction and is particularly concerned with novel means for roofing freight cars.

15 Considerable difficulty has been experienced heretofore in constructing a railroad freight car which would fulfill the loading requirements and at the same time withstand the distortions and strains caused by the shifting of the various classes of freight carried therein. The characteristics of freight loads are so extensive in nature that a freight car construction which would be ideal for withstanding the strains of a particular load, as for instance, grain, sand, etc., would be entirely inadequate to withstand a load in which the weights thereof were unequally distributed in the car. Consequently, the builders of modern cars have developed car frames which may expand, contract or deflect to a limited extent under certain conditions.

20 To meet the requirements of a practical car roof construction it is quite essential that the roof be composed of non-corrosive metallic sheets of such size as to permit of their ready handling by the car builder. A further requirement is that the individual members, the aggregate of which compose the roof, must be relatively movable while being maintained in relative position by weatherproof joints.

25 Wherefore, the general object of my invention is to provide a car roof having flexible characteristics and which will remain weatherproof irrespective of any lateral and longitudinal distortion or deflection of the car body. A more specific object is to provide a standard flexible roof of sufficient

durability that may be easily applied to any make of freight car without necessitating the use of special parts.

30 Other objects include the provision of means for securing such a roof to a car body which will not restrict the relative shifting or weaving motion of the roof and car body.

35 Another object is to provide a roof construction wherein the constituent members may be properly ventilated under all weather conditions and which will likewise permit free circulation of air therethrough.

40 A further object is to provide a novel arrangement of the individual roof members whereby all the foregoing objects may be attained without having nail perforations through the exposed surfaces thereof that may develop leaks when the car body is strained in rounding curves while in transit, or when being switched from place to place at the railroad terminals.

45 Other objects will become apparent as I proceed with a description of the accompanying drawings which illustrate a preferred embodiment of my invention, the essential characteristics being summarized in the claims.

50 In the drawings, Fig. 1 is a perspective representation of a car body with my roof construction affixed thereon, while Fig. 2 is a fragmentary plan view of a part of the roof and running boards, while Fig. 3 is a section through the ridge-beam of the car along the line 3—3 of Fig. 2. Figs. 4 and 5 are sectional elevations of the eave-beam and sheet members taken along the planes 4—4 and 5—5 respectively of Fig. 1, while Fig. 6 is a transverse section along the line 6—6 of Fig. 2. Fig. 7 is an end perspective view of the car roof, while Fig. 8 is a perspective view of an anchor-block herein-after described. Fig. 9 is a longitudinal section through the center of ridge-beam of the car, while Fig. 10 is a bottom perspective view of an end saddle-block, and Fig. 11 shows a top plan view of the intersection of four adjacent roof sheets at the ridge pole with the ridge cap omitted.

I have found that a car roof of the unit construction type may be made flexible by having trough strips extending transversely of the car roof over which the ends of the roof sheets terminate.

Referring to the various parts by numerals, in Fig. 1 I have shown a roof comprised substantially of sectional sheet members 11 resting on the roof boards 11^a disposed on each side of the ridge-beam 33 and terminating thereover in the tapered flange portions 12, the outer edges 12^a of which are adapted to rest in contact on the inner surface 14 of the ridge-cap 13 as shown in Fig. 1 and Fig. 3. The side edges of these sheets are bent to form U-shaped loops 15, which are adapted to surround similar inverted loops 16 formed on the drain strip 17 as shown in Fig. 6; both loops being proportioned to provide air spaces 18, 19, 20 and 21 therebetween. The purpose of this arrangement will be hereinafter referred to. The eave-ends 22 of these roof sheets are bent downwardly and inwardly forming projecting flanges 23, while the eave-ends 24 of the drain strip 17 are likewise bent inwardly in a similar manner; both being disposed within the loop portion 25 of the side flashing 26. This flashing, which extends along the eave the full length of the car body, may have an upwardly projecting portion 27 against which the eave ends of the roof boards 11^a may abut, with suitable notches cut thereinto to permit the extended portion 29 of the drain strip 17 to extend therethrough. It is desirable that the end 23 of the roof sheeting 11 should lie in a different plane within the loop portion 25 of the flashing 26 than the turned-in end 24 of the drain strip. I prefer to have these overlapping and underlapping portions spaced from each other in such a manner that any distortions or displacements which may take place between the drain strip, the roof sheeting or the side flashing will not cause them to come in contact with each other.

The drain strip 17 which is of a channel construction is preferably extended the full width of the car from eave to eave, the strips being bent at the ridge-beam to conform to the roof slopes with each end terminating in the side flashings in the manner as hereinbefore described.

I have shown the ridge-cap 13 as being secured to the ridge-beam of the car by means of the saddle-blocks 30, which are arranged to span the ridge cap, the sides of the roof sheeting and the drain strip. These saddle-blocks are secured to the ridge-beams by anchor bolts 31, the heads 31^a of which are removably secured to the anchor blocks 32, which may be secured to the ridge-beam 33 by any appropriate means such as the bolts 34. These anchor blocks

may be manufactured from any suitable metal, such as malleable iron, with a cored slot 35 and saucer shaped depression 36 adapted to receive the anchor bolt heads 31^a. I prefer to have a recessed passage-way 37 located in the underside of the block through which the drain strip 17 is adapted to pass, as shown in Fig. 8.

As the length of the different freight cars varies, it is essential that the end 75 roof sheet members 39 be of such shape as to provide for these variations, and I, therefore, have arranged this end construction in such a manner that the end member 39 is of sufficient length that the total width 80 of two of these end members will equal a width of the roof sheet 11, and by so doing it is possible to apply this form of roofing to any length of car without necessitating the construction of special end members. 85 The surplus length of the end members, if there be any, may be cut off. These end members may likewise serve as end flashings, whereupon the portion 42 may be secured directly to the car body member 43 90 in the usual manner, while the portion 40 of the end roof sheet may terminate in a U-shaped loop disposed beneath the side loops 40^a of the roof sheet member 11 as illustrated in Fig. 9.

It is quite essential, however, that the ridge-beam may be used as a securing means for holding the roof portions of these end members in place, and I, therefore, provide an end saddle block 44 of such construction 100 that it likewise may serve as a clamp for the end of the ridge-cap 13, as shown in Figs. 9 and 10; the end of the ridge-cap being closed by bending the sides thereof inwardly to provide a sealed end 13^b therefor. This block is recessed on the under side in such a manner that it may serve to clamp the outer surface of the ridge cap and the closed end 13^b thereof and also the roof surfaces of the end roof sheeting 110 39. The running boards 54 which may be secured to the saddle-blocks 30 may also serve as a securing means for maintaining the end saddle-blocks 44 in position. The center running board 54^a may also serve 115 as a weather shield for the anchor bolt 31.

The roof may be applied to a car body as follows:

The car may first be measured to determine the number of sections to be used, the width of these sections corresponding to the width of one of the roof sheets 11 plus the width of the space 45. One eave flashing may then be secured to the car body along one side while the other may be secured in 120 place as the end of each drain strip is bent therein. An end strip of the proper width may then be laid directly upon the purlins 46, ridge beam 33 and eave beams 33^a. Sufficient roof boards 11^a may then be secured 125 130

to the purlins 46 and ridge beam 33 with their eave ends abutting the portion 27 of the side flashing 26. A drain strip is then laid directly upon the purlins and beams, 5 transversely of the car with sufficient spaces 46^a between the sides of the boards and drain strips, to provide a ventilating medium for the interior of the car, after which the succeeding series of roof boards may be 10 laid with the proper number of drain strips uniformly interspersed therebetween and at the finishing end the other end strip may be secured directly to the beams and purlins.

The roof sheets 11 are then laid directly on 15 the roof boards by matching the U-shaped ends thereof with the U-shaped sides of the drain strips and slid thereover toward the centre of the car until the flange portions 12 of the roof sheets are uniformly spaced 20 from the center of the ridge beams, with the flanged portions 23 terminating within the side flashing loop 25. The anchor-blocks 32 may then be mounted directly upon the ridge beam astride the drain strips with the 25 center of each block superposed on the center of each drain strip. The heads of the anchor bolts 31 may then be inserted in the anchor blocks with suitable metallic lock strips 48 securing the bolts therein. These 30 lock strips may have indented surfaces 48^a surrounding the bolt openings corresponding to the recessed portion 36 of the anchor block 32 and are adapted to fit therein after which the sides of these metallic strips may 35 then be bent downwardly along the sides of the anchor block, thereby maintaining the bolts in a central position relative to the ridge-beam. The ridge-cap 13 may then be placed along the ridge of the roof with 40 the sides 14 thereof in contact with the outer portions of all of the tapered flanges 12 on the roof sheet 11. Surrounding the bolt holes in the ridge cap I have also provided indented areas 51 similar to the indented portion 48^a on the lock strips 48.

The anchor blocks may be secured upon the ridge cap and roof sheets by the nuts 49 and washers 50 and anchor bolts 31, after which the running boards may be secured 50 directly to the saddle blocks, the end saddle blocks being secured to the running boards near the ends thereof and superposed directly over the ends of the ridge cap.

By thus assembling the roof, I am enabled to provide a roof surface which has no openings or perforations exposed to the weather, the anchor bolt 31 being covered by the center running board, and any water which may seep under the board and down 55 the bolt 31 will be trapped by the indented portions 51 and 48^a surrounding the openings of the anchor bolts, whereupon the water seeping through and passing downwardly along the anchor bolt, may be restricted to these areas from which it may 60 seep through into the slotted portion 35 in the anchor-block and thereby be guided directly into the drain strip disposed thereunder and out to the eaves of the car. Furthermore, by omitting the anchor bolts on 65 the end saddle blocks, I have no openings whatsoever in the metallic surfaces of the ends of the ridge cap.

It is also to be seen that by having the inwardly extending flanges 24 and 23 on the drain strip and roof sheeting respectively, disposed within looped portion 25 of the side flashing 26, seepage is prevented from reaching the interior of the car, as the drain strips extend beyond the eave ends of the roof boards and drain the U-shaped portions 21 of the roof sheet members 11 and by having these roof sheets extend slightly beyond the eave ends of the drain strips, I obtain an area-way 56 extending longitudinally of the car which is open to ventilation under all circumstances and which provides an inner drainage way for the free movement of any water therein.

Likewise by providing the spaces 18, 19, 20 and 21 between the sides of the roof sheeting and drain strips, I assure ample ventilation of all the roof members and by so doing prevent any sweating of condensation of moisture on the surfaces thereof 90 which would otherwise start active corrosion. Also by providing sufficient space between the flashing and drain strips, moisture which may seep thereunder, is prevented from penetrating to the interior of the car by means of the loop portion 25 of the end flashing 26, while adequate space is provided to permit the ventilation thereof and which, furthermore, will dry out any moisture present therein.

I have found that by providing the opening 46^a communicating with the drain strip and the interior of the car, the formation of condensation and consequent corrosion may be prevented as an active air circulation is created therebetween.

At the corners of the roof the flashing may be folded down and under as shown at 57, Fig. 7 with the end roof sheet 39 disposed thereover.

It is also to be understood that by providing the tapered flange portions 12^a, adjacent to and in pivotal contact with the sides of the ridge cap, the roof sheet may always be maintained in proper position, irrespective of any shifting of the roof boards thereunder and with the further provision of sufficient space along the eaves between the turned-in heads of the roof sheets and the looped portion of the side flashing, a lateral shifting of the roof sheets towards and away from the ridge-beam may also take place without damage thereto. I have also provided for a shifting movement of the drain strip in that there are no nails 120 125 130

or bolts used to secure these strips to the purlins or beams, the strips being permitted to shift about toward and away from the center of the car or to pivot or rotate about the ridge-beam as conditions may require. It is likewise apparent that the ends of the ridge cap may be spaced a sufficient distance away from the last roof sheet members to provide for ventilation as well as for a shifting movement of these roof sheets without causing a rubbing of the metallic surfaces, which would otherwise remove the protective coating of the surfaces and hasten corrosion. A further advantage in the use of my invention is that if any element of the roof becomes impaired in any manner it is possible to replace the same without removing the entire roof. By thus arranging the individual members to be of uniform size it is possible to adapt this type of roof to any type or size of car, the variations in the length being provided for, in that the end members are always of sufficient width to cover any fractional parts of the roof, which may not be covered by the standard roof sheets.

Furthermore, I have provided a flexible metallic roof in which there are no projections or protruding parts along the roof surface upon which a trainman might stumble or fall.

I claim:

1. In a car roof, the combination of roof sheets disposed transversely of the car body with uniform spacings therebetween and terminating at the ridge thereof, wooden sheathing therebeneath, drain strips extending transversely of the car with the edges thereof disposed beneath the edges of the roof sheathing below the plane thereof, and means, including a ridge cap and saddle blocks, for movably securing said sheets to the car body.

2. In a car roof the combination of roof sheets having downwardly and upwardly extending flanges respectively, drain strips disposed transversely of the car below the plane of said roof sheets and having upwardly extending side flanges, wooden sheathing beneath the roof sheets and intermediate of the drain strips, and means positioned at the ridge of the roof for flexibly securing the roof sheets to the car body, including a ridge cap adapted to be maintained in juxtaposition to the upwardly extending flanges on said roof sheets.

3. In a car roof, the combination of roof sheets having downwardly extending side flanges formed into U-shaped loops extending from ridge to eave and upwardly and downwardly projecting end flanges respectively adapted to be yieldably enclosed by a ridge cap member and an eave flashing member respectively and weather-proofing means including drain members having up-

wardly extending side flanges disposed within the side flanges of the roof sheets and end flanges disposed within looped portions of eave flashings extending longitudinally of the car body.

4. In a car roof, the combination of roof sheets, wooden sheathing therebeneath, eave flashings, and drain strips extending transversely of the car and disposed between portions of the wooden sheathing, said drain strips having flanged ends adapted to be disposed within looped portions of the eave flashings extending longitudinally of the car body.

5. In a car roof, the combination of roof sheets uniformly spaced apart and having flanged perimeters, drain strips disposed between said sheets and means adapted to flexibly retain the roof sheets in relative position, said means including an anchor block, ridge cap and a saddle block, and said saddle block and anchor block being connected by an anchor bolt.

6. In a car roof, the combination of roof sheets having a relative freedom of movement, drain strips disposed between said roof sheets extending from eave to eave of the car, anchor blocks provided with a passage, which block rotatively secures said drain strip to the car, ridge caps spanning the ridge ends of said sheets and said anchor block, a running board saddle secured to the anchor block by a bolt, said ridge cap and anchor block provided with indented perforations for said bolt whereby water is directed into said passage and drain strip.

7. In a car roof, the combination of roof sheets having a relative freedom of movement, a ridge cap adapted to coact with flanged portions on said roof sheets to maintain them in relative position, drain strips disposed between the roof sheets, means for securing the ridge cap to the car body including an anchor member positioned at the ridge of the car body and over the drain strips and an anchor bolt adapted to coact with a saddle block bearing upon the ridge cap, said ridge cap and anchoring members being arranged to drain any moisture on the anchor bolt into the drain strip.

8. In a car roof comprising a framing of purlins and carlines, drain strips extending from eave to eave resting upon and rotatively secured to said framing adjacent its center, roofing boards secured to said framing between said drain strips, and roof sheets extending from the ridge to the eave of the car, resting upon said roofing boards and pivoted to the car at its ridge, said roof sheets, drain strips and roofing boards normally spaced apart from each other to permit ventilation and relative movement between these parts.

9. In a car roof comprising a framing of purlins and carlines, drain strips extending

from eave to eave resting upon and rotatively secured to said framing adjacent its center, roofing boards secured to said framing between said drain strips, and roof sheets extending from the ridge to the eave of the car resting upon said roofing boards, said roof sheets, drain strips and roofing boards arranged to permit ventilation and relative movement between these parts.

10. In a car roof comprising a framing of 10 purlins and carlines, and drain strips extending from eave to eave resting upon and rotatively secured to said framing adjacent its center.

In testimony whereof, I hereunto affix 15 my signature.

CHARLES E. WALTER.
